UNITED STATES PATENT OFFICE.

MONTAGUE H. ROBERTS, OF JERSEY CITY, NEW JERSEY, ASSIGNEE TO AIR REDUCTION COMPANY, INC., OF NEW YORK, N. Y., A CORPORATION OF NEW YORK.

PORTABLE APPARATUS FOR THE STORAGE AND SUPPLY OF COMPRESSED GASES.

1,294,707.

Specification of Letters Patent.

Patented Feb. 18, 1919.

Application filed October 22, 1918. Serial No. 259,289.

To all whom it may concern:

Be it known that I, MONTAGUE H. ROBERTS, a citizen of the United States, residing at Jersey City, in the county of Hudson, 5 State of New Jersey, have invented certain new and useful Improvements in Portable Apparatus for the Storage and Supply of Compressed Gases; and I do hereby declare the following to be a full, clear, and exact 10 description of the invention, such as will enable others skilled in the art to which it app pertains to make and use the same.

This invention relates to a portable apparatus for the storage and supply of compressed gases, such as compressed oxygen, compressed nitrogen, compressed hydrogen, and ethylene.

In the utilization of compressed gases, it is customary to compress the gas in bottles or 20 containers so that a considerable amount of the gas can be confined in a small space for shipment and for convenience of handling, and so that the gas can be utilized at a pressure considerably above atmospheric, or at 25 any desired pressure between that of the gas in the container and atmospheric.

Such bottles or containers commonly have a capacity of about $1\frac{1}{2}$ cubic feet and contain about 200 cubic feet of gas at atmospheric temperature, compressed to a pressure of up to about 1800 lbs. per square inch. The bottles or containers have to be constructed of sufficient strength to withstand the high pressures of the contained 35 gas, and also the rough handling to which they are subjected during shipment and use. They must also be provided with suitable valves for regulating the flow of the gas therefrom and with means for reducing its 40 pressure.

Where a large number of such bottles or containers are shipped, *e. g.* by freight, there is considerable danger of injury or breaking of their valves and of the valve extensions. 45 Furthermore, when any considerable number of containers is required, it is necessary to provide for the necessary supply of charged containers in addition to those which are actually being used, and there is a 50 similar number of empty containers to be returned to the place of recharging. The handling of such a large number of containers involves the tying up of a considerable amount of capital in the containers them-

selves, while the provision of individual containers necessitates the separate handling of both the charged and empty containers at the places of use and of recharging. 55

The present invention provides an improved portable apparatus, whereby the objections and disadvantages above noted are largely overcome, so that there is a materially reduced danger of injury of the containers, and so that the containers can be handled in a simple and improved manner 60 with a minimum of labor and with important economies and advantages in the employment of the compressed gas contained therein. 65

The invention will be described more in detail in connection with certain embodiments thereof illustrated in the accompanying drawings, in which:

Figure 1 shows a portable apparatus adapted to receive the bottles or containers; 75

Fig. 2 is an elevation with parts broken away to better illustrate the construction;

Fig. 3 is an end view of the apparatus, showing the bottles or containers in place, and 80

Fig. 4 is a vertical transverse section showing a modified construction.

Inasmuch as the containers for compressed gases, such as compressed oxygen, nitrogen and hydrogen, are commonly known in the art as "bottles," this term will be used in the further description of the apparatus of the present invention. 85

The apparatus illustrated in the drawings is a portable apparatus mounted upon suitable running gear, such as a freight car or trailer truck, the main platform of the truck being indicated at 1. It is supported from the running gear by springs or otherwise in any suitable manner. This truck is provided 90 with an upright framework secured thereto by bolts or rivets and made up of the upright standards 3 and 4, shown as made of channel iron, the braces 2 of angle iron, and the braces 5 for increasing the longitudinal 95 rigidity of the structure. An upper beam or channel iron member 6 is provided at the top of the framework, and the various members of the frame are suitably riveted or fastened together. 100

The platform of the truck is provided with longitudinal members 7 and 8 suitably secured thereto, and transverse members 9 105

also secured thereto. To these members there is secured, by riveting or otherwise, shaped members 10, 11 and 12, which may conveniently be made of strap iron bent to 5 the proper shape, and which have a contour such that the bottles are confined thereby at their lower ends.

The upper beam or member 6 has secured thereto by riveting or otherwise, shaped 10 members 13 and 14, which are so shaped as to confine the bottles near their upper ends, as best shown in Fig. 3.

Mounted upon the upper beam 6 are the upright supports 15, carrying at their upper 15 ends the channel iron member 17, which extends lengthwise of the apparatus at a level near that of the upper ends of the bottles. Suitably secured upon this beam 17, by straps 18 or otherwise, is a header or mani- 20 fold 19, adapted to have secured thereto a sufficient number of separate pieces of flexible high pressure tubing, so that separate pieces of tubing may lead to each of the individual bottles. These pieces of tubing, 25 indicated at 20 and 21, may be of any suitable length and configuration to permit their attachment to the bottles in the customary manner.

The bottles themselves are arranged in 30 four rows, two on each side of the center of the apparatus, the two inner rows being arranged close to the central part of the framework, and the two outer rows being spaced away therefrom. The arrangement is such that the bottles are staggered 35 and arranged in groups of five, the apparatus as a whole being adapted to carry fifty bottles, all of which are connected by the high pressure tubing to the common 40 header or manifold 19.

Each of the bottles as shown is provided with the usual valves 22 for closing the bottles completely or for permitting flow therefrom of the compressed gas, or inflow 45 of the gas during charging. The arrangement is such that any one of the bottles can be connected with the header or manifold 19 through its respective high pressure tubing 20 or 21, and so that several of the bottles 50 or as many as may be desired can be similarly connected to the header or manifold.

The header or manifold, which is also provided with a master valve (not shown), 55 is made of pieces of larger pipe 23, joined together by the high pressure tubing 24, and having high pressure tubing 25 at its end, so that it can be connected either to a source of compressed gas for purposes of 60 charging the bottles or to a distributing pipe leading to the desired place of use of the bottled gas. By means of the master valve in the header the supply of gas can be shut off or regulated as a whole. Thus one or 65 more of the bottles can be left in communica-

cation with the header, and the regulation effected by the master valve; while the individual valves on the bottles enable independent regulation when desired.

The portable apparatus of the present invention can be taken to the source of the compressed gas, for example, to a liquid air plant, where either oxygen or nitrogen, or both, are separated from the atmosphere and obtained in a state of purity, and the 75 gas can then be compressed by the usual compressors with which such a plant is provided and all of the bottles of the apparatus filled with the gas to the desired pressure. Each of the bottles can then be closed by 80 closing the master valve by closing its individual valve in the usual manner. The apparatus can then be taken to the place where the bottled gas is to be used, for example, to a plant where oxygen is required 85 for welding or cutting purposes, and the distributing main or pipe of the plant can be connected with the header 19 to supply the gas to such parts of the plant where it may be required.

In the use of the compressed gas, one or more of the bottles can be connected with the header and will supply its gas thereto until exhausted or until its pressure has fallen to that of the pipe into which it is 95 supplied. If desired, all of the bottles may be connected with the header, so that a continuous supply of the gas will be obtained until the entire supply has been used up. The header 19 can then be disconnected, 100 and the apparatus returned to the source of supply of the gas, so that the bottles may be recharged.

It will be seen that the apparatus provides for the supply of a large amount of 105 compressed gas (50 bottles in the particular apparatus illustrated) with a minimum of handling and labor. In fact, the only operations necessary for the charging of the bottles and the utilization of the compressed 110 gas are the operations of manipulating the particular valves to connect or disconnect any particular bottle or bottles with the common header or manifold. The individual bottles are thus protected against break- 115 age from rough handling and the bottles themselves do not require individual handling, nor do they require to be separately connected and disconnected with the pipe or apparatus to which the gas is to be supplied. Instead, the common header or manifold can be directly connected and part or all of the bottles may then be connected thereto and the gas therein made available without any additional operations whatso- 120 ever.

The portable apparatus of the present invention not only provides for the supply of a large amount of gas in a convenient manner, but it provides for the conveyance of 130

this large amount of gas in a convenient and advantageous manner. The structure of the apparatus is such that the individual bottles are kept separate from each other, so that 5 there is no danger of injury of the bottles by each other. The bottles are also protected from injury while they are being conveyed from the place of charging to the place of use, for the reason that the bottles 10 are individually held upon the truck and are confined so that they are prevented from any considerable movement. At the same time, the construction of the members 10 to 14 inclusive, of a material such as strap 15 iron, which is itself flexible or yieldable, provides for the absorption of any shocks during transportation, the yieldable supporting straps acting as shock absorbers. Some slight movement of the bottles with 20 respect to each other and with respect to the apparatus as a whole is thus permitted, while the high pressure tubing 20 and 21 (pig-tails, so-called) permits this movement without interference with the connections of the 25 individual bottles with the common header.

In the charging of the bottles it is customary to make use of a water-lubricated pump or compressor with the result that more or less moisture is carried into the bottles with 30 the gas and collects therein. Unless this water is removed it will remain and accumulate with successive rechargings. The modified form of apparatus of Fig. 4 is arranged to provide for the removal of this 35 moisture, so that it cannot accumulate in the bottles. To that end, the apparatus of Fig. 4 provides for supporting the bottles in an inverted position, so that any liquid therein may be first removed upon the opening 40 of the respective valves, and will be thereby eliminated.

In the apparatus of Fig. 4, corresponding parts are indicated by the same characters used in Figs. 1 to 3, but with the suffix *a* 45 appended thereto. The floor 1^a of the truck is provided with a series of openings for the individual bottles, of a size which will permit the necks of the bottles to project therethrough, but which will not permit the bottles 50 as a whole to pass therethrough. These openings accordingly confine the necks of the bottles and make unnecessary the provision of any separate confining means, such as is provided for the bottoms of the bottles 55 in the apparatus of Figs. 1 to 3. The upper ends of the bottles of Fig. 4 are confined in a similar manner to that illustrated in Figs. 1 to 3. The header 19^a of Fig. 4 is arranged below the truck platform and is suitably secured to a beam or member 17^a secured to 60 the under side of the truck platform or its supporting members. The apparatus of Fig. 4 has the same or similar advantages to the apparatus of Figs. 1 to 3, but it has the added advantage of providing for the removal 65

of any moisture contained in the bottles, so that accumulation of moisture therein is prevented.

It will of course be understood that the apparatus may be built in different sizes and 70 to carry a larger or smaller number of the individual bottles; and it will likewise be understood that the specific construction illustrated and described can be modified without departing from the spirit and scope 75 of the invention. The apparatus of the present invention is available for use in the storage and transportation of various compressed gases. The apparatus may thus be charged with oxygen gas at an oxygen plant 80 and the gas may then be transported to its place of use, for example, for welding or cutting purposes. The apparatus can similarly be charged with hydrogen or ethylene at the plant where such gases are produced 85 or separated, and the apparatus can then be conveyed to any suitable place where the gas is desired. The apparatus when charged with pure nitrogen gas at a nitrogen plant can be likewise conveyed to the place of use 90 of the nitrogen, for example, for illuminating purposes (as in incandescent bulbs) or where a supply of an inert gas is desired. Combustible gases may be similarly stored and transported and rendered available for 95 use. Of course, if only part of the gas is required, a part only of the bottles need be used, and the remainder of the gas will be retained in the remaining bottles and will be available for use elsewhere or at some 100 other time.

I claim:

1. A portable apparatus for the storage and supply of compressed gases, comprising a truck or vehicle having a supporting platform or framework, means for securing thereon a plurality of upright bottles or containers of compressed gas, a common header for the said bottles or receptacles, and means for connecting said bottles or receptacles with said common header. 105

2. A portable apparatus for the storage and supply of compressed gases, comprising a truck or vehicle having a framework secured thereto and extending thereabove, 110 means connected to said platform and framework for engaging and confining a plurality of separate bottles or containers adjacent their opposite ends and out of contact with each other, a common header supported 115 by said framework, and means for connecting said respective bottles or containers with said common header. 120

3. A portable apparatus for the storage and supply of compressed gases, comprising a truck or vehicle having a central framework secured thereto and extending thereabove, means secured to said framework for confining a plurality of separate bottles or receptacles near their upper ends, means for 125 130

similarly confining said bottles or receptacles at their lower ends, a common header secured to said platform and framework, and independent means for connecting each of said 5 bottles or receptacles with said header.

4. A portable apparatus for the storage and supply of compressed gases, comprising a truck or vehicle having a supporting platform or framework adapted to support a 10 plurality of upright bottles or containers of compressed gas in an inverted position, a common header for the said bottles or receptacles, and means for connecting said bottles or receptacles with said common 15 header whereby any liquid contained therein can be readily removed.

5. A portable apparatus for the storage and supply of compressed gases, comprising a truck or vehicle having a platform and 20 having a framework secured thereto and extending thereabove, said platform being provided with openings for supporting and confining the upper ends of bottles or receptacles in an inverted position, means connected to said framework for confining the 25 other ends of said bottles or receptacles, a common header for the bottles or receptacles, and independent means for connecting each of said bottles or receptacles with said 30 header.

6. A portable apparatus for the storage and supply of compressed gases, comprising a truck or vehicle having a platform and

having a framework secured thereto and extending thereabove, means secured to said 35 framework for yieldingly confining a plurality of separate bottles or receptacles for compressed gas near their upper ends, means in connection with the platform for confining said bottles or receptacles at their 40 lower ends, a common header for said bottles or receptacles, and means for connecting said bottles or receptacles with said common header whereby the supporting means for securing said bottles or receptacles act as 45 shock absorbers to prevent injury during transport.

7. A portable apparatus for the storage and supply of compressed gases, comprising a truck or vehicle having a platform and 50 having means in connection therewith for confining a series of bottles or receptacles of compressed gas at their lower ends, a central framework secured to and extended above said platform, means secured to said 55 framework for confining the said bottles or receptacles near their upper ends, a central header extending the length of said truck or vehicle and suitably supported thereby, flexible high-pressure tubing connecting each 60 of said bottles or receptacles with said header, and independent means for connecting or disconnecting any one or more of said bottles or receptacles with said header.

In testimony whereof I affix my signature. 65
MONTAGUE H. ROBERTS.
